UNITED STATES PATENT OFFICE.

WILHELM FRIEDRICH LUDWIG BETH, OF LÜBECK, GERMANY.

CLEANING FILTER-CLOTHS IN DUST-COLLECTORS AND THE LIKE.

No. 833,117.

Specification of Letters Patent.

Patented Oct. 9, 1906.

Application filed February 16, 1905. Serial No. 245,982.

To all whom it may concern:

Be it known that I, WILHELM FRIEDRICH LUDWIG BETH, manufacturer, a subject of the German Emperor, residing at Lübeck, Empire of Germany, have invented certain new and useful Improvements in the Cleaning of Filter-Cloths in Dust-Collectors and the Like, of which the following is a specification.

- 10 This invention has for its object an improvement in the dust and like filters in which the layer of material pervious to air retains the dust or other matter and must from time to time be freed from the same.
- 15 This end is at present attained more particularly in tubular filters or trunks by the filtering material, which during the separating operation is stretched taut, being temporarily slackened, so that it lies in waves or folds, 20 after which it is again stretched taut as suddenly as possible. By this method of operating and cleaning the material employed suffers much, as it is constantly stretched and by the sudden restretching after being 25 released or creased during the cleaning operation undergoes a great strain. Now this invention removes this drawback by the filtering material (tube or sleeve) not being stretched during the working, but left loose.
- 30 The air-current flowing through the material spreads the fabric in slight curves or domes and smooths it out in spite of its looseness.

In the drawings, Figure 1 is a side elevation, partly in section, of tubular filter in accordance with this invention; and Fig. 2 is a fragmentary section thereof.

- 35 Referring to the drawings, wherein like reference characters denote corresponding parts throughout both views, *a* designates a plurality of tubular filters, one arranged above the other and suitably connected together. Said filters *a* may be of any preferred material. As shown in the drawings, two sets of filters are employed, and they are inclosed in a case *h*.
- 40 The lower end of each set of filters is secured in any suitable manner to near the lower end of the case *h*, while the upper end of each set of filters has connected thereto a cover *f*. The covers *f* are suspended by means of a rod *g*, the 45 latter being substantially T-shaped and has the ends of the lower terminal thereof suitably connected to the covers *f* and its upper terminal attached to one of the arms of a double-arm lever *b*, the latter being pivotally connected intermediate its ends exteriorly of and upon the top of the case *h*. A rotating

cam member *d* is positioned in operative relation with respect to the other arm of the lever *b*, and the said rotating cam member *d* is adapted to engage the lever *b* to actuate it. 60 The case *h* is provided with an outlet for the exhaust, and said outlet is controlled through the medium of a cut-off valve *e*. To limit the movement of the said rod *g*, a stop *i* is provided, the said stop *i* being carried by the 65 rod *g* and is adapted to encounter a support *c* on the case *h* during the downward movement of the rod *g*, consequently arresting the movement of the said rod when the latter is moving downwardly. When it is desired to 70 clean the filters, the air is shut off by means of the valve *e* in the ordinary manner. The covers *f* of the filters *a* are then lifted by the cam *d*, acting upon the rotating cams *d* and a two-armed lever *b* without causing a sudden 75 and taut stretching. After the cam *d* has slipped from under the lever *b* the tubes or sleeves close or shut down under the action of their own or of the special weight or under the action of the spring. This fall is arrested 80 by a stop *i*, connected with the suspension-rod *g*, which stop encounters a support *c*, and thereby produces so violent a shaking of the sleeve or tube that the dust adhering to the material drops off. 85

I declare that what I claim is—

In a device of the class described, the combination with a case, two sets of tubular filters arranged therein, one terminal of each set of filters being secured to the case, and 90 covers secured to the other terminal of each set of filters, of means for gradually stretching and suddenly releasing the filters, said means consisting of a suspension-rod connected to the said covers, a double-arm lever 95 pivotally connected intermediate its ends to the exterior of the case and having one arm thereof attached to said suspension-rod, and a rotatable cam member arranged adjacent to the other arm of said lever and adapted to 100 actuate the latter at intervals, said cam member being normally free from engagement with the said lever until brought into position to contact therewith during its rotary movement. 105

In testimony whereof I have hereunto set my hand in presence of two subscribing witnesses.

WILHELM FRIEDRICH LUDWIG BETH.
